UNITED STATES PATENT OFFICE.

CARLOS N. BRUZAUD, OF PEEKSKILL, NEW YORK, ASSIGNOR OF ONE-THIRD TO ROSA D. KORNHAUSER, OF PEEKSKILL, NEW YORK.

BROOCH.

No. 902,274.

Specification of Letters Patent.

Patented Oct. 27, 1908.

Application filed June 13, 1907. Serial No. 378,735.

To all whom it may concern:

Be it known that I, CARLOS N. BRUZAUD, a citizen of the United States, residing at Peekskill, in the county of Westchester and State of New York, have invented new and useful Improvements in Brooches, of which the following is a specification.

This invention relates to a combined brooch and manicure article or the like, and has for its principal object to provide in a piece of jewelry, a useful article that may be employed as a paper cutter or manicuring instrument.

A further object of the invention is the provision of a brooch in the form of a sword or sheath, the blade of the sword serving as a paper cutter and a nail file and knife, means being employed for locking the sword in place.

With these objects in view and others, as will appear as the description proceeds, the invention comprises the various novel features of construction and arrangement of parts which will be more fully described hereinafter and set forth with particularity in the claims appended hereto.

In the accompanying drawing, which illustrates one of the embodiments of the invention, Figure 1 is a front view of the combination brooch. Fig. 2 is a view showing the sword removed from the scabbard or sheath and the latter in section. Fig. 3 is a top view of the brooch. Fig. 4 is a section on the line 4—4, Fig. 3.

Referring to the drawing, A designates the sword, and B, the sheath or scabbard therefor and both forming together the brooch. The front side of the sheath and heel of the sword are suitably ornamented so as to present an attractive piece of jewelry, and on the back of the sheath is a pin 1 hinged at 2 and adapted to engage in a keeper 3, whereby the brooch can be attached to the garments of the wearer. The blade 4 of the sword has its edge 5 sharpened throughout the outer half thereof and the remaining part is roughened at 6 to form a nail file, the sharp edge serving as a paper cutter or a nail trimmer.

In order to hold the sword in the sheath, the heel 7 of the blade is provided with a

transverse opening 8 extending inwardly from the back edge of the blade and the scabbard has an opening 9 adapted to register with the opening 8, and extending through the opening is a pin 10 that snugly fits the latter so as to be frictionally held in place, thereby locking the sword in the scabbard. The outer end or head 11 is suitably shaped and ornamented and the bottom or opposite side of the scabbard has an ornamented projection 12 to correspond with the head of the pin so as to make the arrangement symmetrical.

The brooch is worn with the sword locked in position as shown in Fig. 1 and whenever it is desired to take out the sword for cutting open an envelop or the like or for trimming and filing the nails, the locking pin 10 is withdrawn to permit the sword to be taken out and the locking pin can be replaced in either the scabbard or sword so as not to be lost. To take out the sword, it is unnecessary to unpin the scabbard from the garment.

Having thus described the invention, what I claim is:

1. A brooch comprising a sheath having an aperture in its wall and an ornamental projection arranged opposite the aperture, a sword consisting of a blade and a handle, said blade having a transversely extending aperture adapted to register with the aperture of the sheath, said blade forming a cutter and a nail file, and a locking pin having a shank portion extending through the aperture of the sheath and into the aperture of the sword and having a head disposed outside the sheath to form an ornament corresponding to the projection and serving as a grip for facilitating the removal and insertion of the pin.

2. A brooch comprising a hollow sheath open at one end and having an aperture adjacent the open end and at the top side of the sheath and provided with an ornamental projection depending from the bottom side of the sheath at a point opposite from the aperture, a member extending into the sheath and provided with transversely-extending opening adapted to register with the aper-

100

ture of the sheath, a locking pin having a shank portion proportioned to fit in the aperture of the sheath and opening of the member and having its upper end formed into a head disposed outside the sheath at a point opposite from the said projection and serving as a grip for facilitating the removal and insertion of the pin, and means on the back of

the sheath for securing the brooch in position.

In testimony whereof, I affix my signature in presence of two witnesses.

CARLOS N. BRUZAUD.
